IMPULSE REPEATER

Harry G. Evers and George Elliott, Chicago, Ill.,
assignors to Automatic Electric Laboratories,
Inc., a corporation of Delaware

Application February 15, 1943, Serial No. 475,904

16 Claims. (Cl. 179—16)

The present invention relates in general to signalling systems and more particularly to impulse repeaters for use in automatic telephone systems.

The object of the present invention is the provision of an improved impulse repeater, or long line adapter, for use with long telephone lines.

A feature of the present invention is the provision of a more sensitive receiving circuit at the exchange to insure quick and accurate response to dial impulses created at the subscriber's instrument on long or heavily loaded telephone party-lines.

A further feature is a new and improved circuit network in which the impulse relay is a polarized relay having a plurality of windings included in both the line circuit and in local circuits to enable the impulse relay to quickly and accurately respond to the opening and closing of the line during impulsive. One of the windings of the impulse relay being connected in series with a condenser and is connected over the line and over a local circuit in such a manner that current flow in this winding is quickly reversed during impulsive to cause the relay to quickly respond to the subscriber's dial impulses. In addition, this winding is connected in another local circuit of high resistance during each closed pulse period, after the condenser in the first mentioned local circuit is charged, and is thereafter effective so that this winding is preenergized in a direction to cause quick restoration of the impulse relay when the line is opened. The other winding of the impulse relay is also connected in series with the line and is connected in a local circuit in such a manner that current flow in this winding is likewise reversed during impulsive to assist in the operation of the relay so as to accurately follow the impulses. In addition the local circuit for this latter winding assists in maintaining the impulse relay in its released position during the open pulse period so that any minor line disturbances will not effect the relay. This latter winding is energized over the line during the line closure periods to maintain the relay in its operated position.

The invention and various features of improvement comprised therein will be described herein-after in connection with the accompanying drawings, in which:

Fig. 1 shows by means of the usual circuit diagrams an impulse repeater, or long line adapter, individual to a long heavily loaded telephone party line.

Fig. 2 illustrates diagrammatically that portion

of Fig. 1 which relates to the impulsive arrangement.

Fig. 3 shows a modification of the repeater when used on a grounded line.

Fig. 4 illustrates diagrammatically that portion of Fig. 3 which relates to the impulsive circuits.

Referring now more particularly to Fig. 1 of the drawings, there is illustrated in partially schematic form a long telephone party line heavily loaded with ringers, an impulse repeater, or long line adapter, individual to and terminating the line in the telephone exchange, and the individual line circuit by means of which incoming and outgoing calls are extended from and to the automatic switching apparatus in the automatic exchange.

The line, comprising conductors 1 and 2, is a long telephone party-line having a plurality of 20 subscribers' substations, such as A, B and C, connected thereto. At each substation there is a ringer and a condenser connected in series to one of the line conductors and ground. The line conductors 1 and 2 terminate in the automatic exchange in an individual impulse repeater, or 25 long line adapter, comprising a plurality of relays and a repeating coil. The other end of the repeater terminates in the well-known line circuit, comprising the usual line and cut-off relays, used 30 in automatic telephone. This line circuit is provided with the usual incoming and outgoing branches for completing calls to and from the line. The relays in the repeater are of the type used in automatic telephone systems except that 35 relay 70 is a sensitive polarized relay having a permanent magnet and two windings, one a primary winding P and the other a second winding S. Polarized relays of this type are well-known and have been used in telegraph systems.

Fig. 2 diagrammatically shows only that portion of Fig. 1 which relates to the transmission of subscriber's impulses over the line to the impulse receiving network at the exchange which is effective during impulsive to operate the polarized pulsing relay 70.

Corresponding apparatus in Figs. 1 and 2 have been given the same reference character or numeral. This form of circuit diagram in Fig. 2 has been shown in order to more readily see and understand the operation.

Fig. 3 illustrates the same repeater, as shown in Fig. 1, when connected to a grounded subscriber's party-line. In this figure the circuits are slightly altered so that this repeater will function properly over a grounded telephone

party-line, such line comprising only a single conductor grounded at the substations on this line and also grounded at the exchange as illustrated. The alterations are easily noted when Fig. 3 is compared with Fig. 1 especially since corresponding apparatus have somewhat similar reference characters, in that such reference characters have been primed and the reference numerals increased by one hundred.

Fig. 4 diagrammatically shows only that portion of Fig. 3 which relates to the transmission and receipt of subscribers' impulses over the grounded party lines. Corresponding apparatus in Figs. 3 and 4 have been given the same reference character or numeral.

The operation of the system will now be described in detail in connection with Figs. 1 and 2. For this purpose it will be assumed that subscriber A initiates a call by removing his receiver whereupon a circuit may be traced from ground thru the winding of relay 40, winding 25 of repeat coil RP, back contact and armature 22, back contact and armature 12 out over the subscribers' line conductor 2, calling device CD of substation A, switchhook contacts, line conductor 1 back to the exchange, armature 11 and back contact, armature 23 and back contact, winding 24 of repeat coil RP, to junction point 29 where the circuit divides one branch extending thru the winding of relay 50 to battery and the other branch extending from junction point 29 by way of armature 33, primary winding P of the polarized pulsing relay 70, and thru the condenser C to battery. Relays 40 and 50 are energized in series over the calling subscriber's loop and at armatures 50 and 51 complete an obvious circuit for energizing slow-to-release relay 90. The condenser C is charged over the previously traced circuit including the primary winding P, the subscriber's loop and the winding of relay 40. The charging current thru the primary winding P is in a direction to cause the relay 70 to operate and close its armature 71 to thereby complete an operating circuit to the pulse repeating relay 80.

Relay 90, upon energizing at armature 94, disconnects ground from the circuits of the ring control relays RC1 and RC2; at armature 93 closes one point in the loop circuit comprising conductors 3 and 4 for operating the line relay (not shown) in the line circuit; and at armatures 91 and 92 connects battery and ground thru resistances R2 and R1 respectively to the secondary winding S of the polar impulsing relay 70.

The pulse repeating relay 80, upon energizing, at armature 81 completes another circuit for slow-to-release relay 90 in order to maintain this relay in operated position during dialling independent of armatures 41 and 51; at armature 82 connects ground by way of armatures 92 and 82 thru the high resistance R3 to the primary winding P and condenser C; and at armature 83 completes the loop circuit over conductors 3 and 4 for operating the line relay of the line circuit.

The line relay (not shown) in the line circuit operates and in the well-known manner and causes a line switch or finder to operate and connect the conductors 3 and 4 to one of the first numerical switches in the automatic exchange. Such numerical switch being either a selector or connector dependent upon the number of subscribers' lines being served by this exchange. Dial tone is transmitted back from the 75

first numerical switch over conductors 3 and 4 and thru the repeat coil RP and over the subscribers' line conductors 1 and 2 to inform the calling subscriber that he may now proceed to dial the digits of the desired called subscriber's number.

Before proceeding with the dialling operation, we will return to the time when relays 80 and 90 operated to close certain local auxiliary circuits to aid in the operation of the impulsing polar relay 70. When relays 80 and 90 have operated, the circuits in Fig. 2 have been interconnected as shown. It will be remembered that condenser C is receiving a charge thru the primary winding P of relay 70 from over the line and thru the winding of relay 40. The current flow in this circuit is sufficient to operate the polar relay 70 and before the condenser C is fully charged a holding circuit thru the secondary winding S is completed in such a direction to assist in the operation of the polar relay 70 and to maintain the polar relay in its operated position after the condenser C is fully charged. The circuit thru the secondary winding S may be traced as follows: from ground thru the resistance R1 to point 84 where the current divides one path extending over resistance R2 to battery and the other path extending thru the secondary winding S of relay 70, over the closed subscriber's loop, and thru the winding of relay 50 to battery. The current flow in this latter path thru the secondary is in a direction to assist in the operation of the polar relay 70 and, also, is sufficient to hold the relay in operated position after the condenser C is charged and no current flows in the primary winding P. Another local circuit connects ground thru the high resistance R3 to the primary winding P of relay 70 at junction point 86, this circuit is effective after the condenser C is charged to cause a slight current flow thru the primary winding P in the reverse direction. This circuit may be traced as follows: from ground thru the high resistance R3 to junction point 86 thru the primary winding P of relay 70, and thru the winding of relay 50 to battery. As will be noted this current is in the reverse direction to that of the condenser charging circuit but due to the high resistance of resistance R3 the current flow merely pre-energizes the primary winding in a direction to cause the quick release of this relay when the line circuit is opened. The previously traced circuit thru the secondary winding S of relay 70 predominates over this preenergizing circuit of the primary winding to hold the relay operated until such time as the line circuit is opened. The polar relay 70 is therefore held in operated position until the subscriber starts to dial the called subscriber's number or until the calling subscriber hangs up his receiver.

The resistance values of the resistances R1, R2 and R3 and the capacitance value of the condenser C, included in the local network circuits, have been carefully chosen and by actual practice have permitted very satisfactory performance over long telephone lines heavily loaded with ringers. The resistance value of resistance R2 in combination with resistance R1 has been chosen to exceed the overall resistance of the line in combination with the battery feed relays 40 and 50 when the line is closed and should be less when the line is open in order to reverse the current in the secondary winding S. The capacity of condenser C

is of such a value as to give a sustained charge or discharge current flow thru the primary winding P for a predetermined time. The resistance value of the resistance R3 is relatively high compared with the line resistance in combination with the battery feed relays to limit the preenergizing reversal of current in the primary winding P.

The calling subscriber, after receipt of dial tone, may dial the digits of the desired called subscriber's number. At the instant the calling device CD is operated to open the subscriber's loop the local discharge circuit for the condenser C thru primary winding P is effective to cause the release of polar relay 70. This circuit may be traced as follows: from negative battery, condenser C, thru the primary winding P of relay 70, armature 33, point 29 and thru the winding of relay 50 to negative battery. The current flow in this local circuit is in the same direction as in the previously traced preenergizing circuit for this winding. At the instant the line is opened the ringer condensers in the line are being charged but the discharge current from condenser C thru the primary winding P has a tendency to neutralize the charging current to the ringer condensers. Also at the instant of line opening there is only momentarily a current flow thru the secondary winding S in a direction to maintain the relay in its operated position but due to the rapid rise in resistance in the line as the ringer condensers are being charged, the current flow in the secondary winding S is very quickly reversed to assist the primary winding in releasing relay 70 to its released position. The local circuit for the secondary winding S, during the open pulse period when the line is open, may be traced as follows: from ground thru the winding of relay 40, junction point 28, armature 32, secondary winding S, junction point 84, armature 91 and thru resistance R2 to battery. The current flow in this circuit is sufficient and in a direction to both assist the primary winding P to release the relay 70 and maintain said relay in its released position. This local circuit for the secondary winding S is effective before the condenser C is discharged. Pulse repeating relay 80 deenergizes in response to the release of relay 70 to disconnect ground thru the high resistance R3 from the primary winding P to open the previously traced preenergizing circuit for the primary winding. When the condenser C is fully discharged in its local circuit no current flows thru the primary winding and the relay 70 is maintained in its released position by the current flow in the secondary winding S thru the resistance R2. It should also be mentioned that after the discharge of condenser C and when the line is open that relay 50 may momentarily release during dialling but such releasing operations of relay 50 are ineffective because the relay 90 is slow acting and will be maintained in operated position during dialling.

The pulse repeating relay 80 is operated over an obvious circuit by the polar relay 70 operating its armature 71 and it should be mentioned that the resistance R4 and condenser C1 connects ground to junction point 72 to quench the sparks at armature 71 and to act as a so-called "pulse-stretcher", in that, due to the charging and discharging circuit of condenser C1, the pulse-repeating relay 80 somewhat lengthens the pulses repeated at armature 83 to more nearly conform to the standard pulsing rate normally used in automatic telephone systems. At armature 83, the pulse-repeating relay repeats the pulses over the conductors 3 and 4 to the automatic switches in the exchange to cause these switches to com-

plete the desired connection in a well-known manner.

When the calling device CD closes the line circuit after the open pulse period, circuits are completed over the line for relays 40 and 50 and for both the primary and secondary windings of relay 70. The circuit for relays 40 and 50 extends from ground, relay 40, over the closed subscriber's loop including the windings 25 and 26 of the repeat coil RP and the line conductors 1 and 2, and winding of relay 50 to battery. The circuit for the secondary winding S extends from ground at armature 92 thru resistance R1, secondary winding S of relay 70, over the subscriber's line loop including the repeat coil windings 24 and 25, and thru the winding of relay 50 to battery. A branch of this latter circuit extends from junction point 29 and armature 33 thru the primary winding P of relay 70 and thru the condenser C to battery for charging condenser C thru the primary winding P. The current flow in the secondary winding S since the line is closed, and the charging current flowing in the primary winding are in a direction to aid each other to cause relay 70 to operate to its operated position. Since the resistance of resistance R2 is greater than the line resistance, comprising the subscriber's loop, the current thru the secondary winding S again reverses to aid in the operation of relay 70 as well as for maintaining the relay in its operated position after condenser C is charged.

Relay 70, upon operating, closes armature 71 to again operate pulse repeating relay 80 which at armature 83 again closes the loop to the automatic switch train. At armature 81 relay 80 again closes the circuit to slow relay 90 and at armature 82 again connects ground thru high resistance R3 to the primary winding P thereby preparing the previously described preenergizing circuit for the primary winding P which is effective after the condenser C is charged. The previously traced circuit thru the secondary winding S maintains relay 70 in operated position, as previously described, until the line is opened for the second pulse of the called number.

Further impulses of the called subscriber's number cause the circuits and relays 70 and 80 to function in the same manner as previously described thereby operating the automatic switches in the automatic exchange in the well-known manner to complete the desired connection. Talking battery is fed thru the windings of battery feed relays 40 and 50. After conversation and in response to replacing the receiver the subscriber's line is opened and relays 70 and 80 release to cause the release of the automatic switch train. Relays 40 and 50 likewise release to cause the release of slow acting relay 90 after a short interval and the repeater is now in normal unoperated position.

Having described the operation of the repeater in connection with an outgoing call from the subscriber's line, an incoming call will now be described to one of the subscribers on this line. As will be noted, the ringers L1 to L3 at the various substations on this line are connected to one of the line conductors and ground. In order to selectively ring a subscriber on this line divided code ringing is applied from an automatic connector switch. Automatic Strowger connector switches of this type are well known and need not be described. Patent 2,099,429 shows a Strowger connector switch utilizing divided code ringing while Patent 2,023,239 shows

an all-relay connector switch utilizing the same type of selective ringing arrangement. For selectively signalling subscribers A and C ringing current is sent out over the line conductor 1 and the ringing code sent determines which subscriber A or C is wanted. In a similar manner ringing current is sent out over line conductor 2 for all subscribers having their ringers connected in the same manner as ringer L2 for substation B. It will now be assumed that an automatic switch has been operated to connect with conductors 5, 6 and 7 individual to this party line and that the call is intended for subscriber A. The automatic connector therefore connects ringing current to conductor 7 in the code assigned to subscriber A. This ringing current extends from the connector switch over conductors 7 and 3, thru winding 26 of repeat coil RP, and thru the winding of ring control relay 60 and condenser RC1 to ground at armature 94. Relay 60 responds each time ringing current is connected to conductor 7, thereby causing the operation of ringing relay 10 alike number of times. Each time ringing relay 10 operates it connects generator GEN at make contact of armature 11 to line conductor 1 thereby operating all the ringers connected to line conductor 1. At armature 12 relay 10 grounds the other line conductor 2 and at armature 13 completes a circuit for operating slow relay 30. Slow relay 30 also follows the ringing code and releases a short interval after ringing relay 10. Relay 30 at armatures 32 and 33 disconnects the windings of the sensitive polar pulsing relay 70 from the line so that this relay will not be falsely operated during ringing. At armatures 32 and 34 connects ground and battery thru resistances R6 and R5 respectively to the windings of relays 40 and 50 to prevent false operation of these relays. Subscriber A, upon recognizing his ring and removing the receiver, completes the previously traced circuit for relays 40, 50 and 70 when the relay 30 deenergizes after the last ringing period. The operation of relays 80 and 90 take place in the same manner as previously described to close a bridge across conductors 3 and 4 to cause the connector to cut off any further ringing operations. The bridge circuit includes armatures 83 and 93, resistance R, repeat coil windings 26 and 27, conductors 3 and 4, conductors 1 and 5, and the ring-cut-off relay in the connector switch. Talking battery is fed over the windings of relays 40 and 50 to subscriber A. After the conversation and in response to hanging up the receiver at substation A relays 40, 50, 70, 80 and 90 deenergize to restore the repeater to normal while the connector switch is released in the usual manner.

In case subscriber B is being called then the connector switch applies ringing current to conductor 5 in code thereby causing the operation of ring control relay 95 for each application of ringing current. The circuit for relay 95 may be traced as follows: ringing current from the connector switch, conductor 5, conductor 4, winding 27 of repeat coil RP, ring control relay 95, condenser RC2 to ground at armature 94. Each operation of relay 95 causes a like operation of ringing relay 20. Relay 20 in a manner similar to that described for relay 10 operates slow relay 30 at armature 21, at armature 23 grounds line conductor 1 by way of back contact and armature 11, and at armature 22 connects generator GEN by way of conductor 2 to ring all of the ringers connected to conductor 2. Sub-

scriber B, upon recognizing his code ring, answers by removing the receiver thereby causing the operation of relays 40, 50, 70, 80 and 90 in the same manner as previously described. The operation from here on is the same as for a call to substation A and need not be described in detail.

As previously stated the modification shown in Fig. 3 is substantially the same repeater as shown in Fig. 1 adapted for use on a grounded party line. This party line comprises a single line conductor 101 extending from the exchange and is grounded at the various substations on the line. In this modification the pulsing circuit for the polarized relay 170 is slightly different, in that the secondary winding S is now connected in a reverse direction to that shown in Fig. 1 and the resistances R2' and R1', corresponding respectively to resistances R2 and R1, are interconnected between battery and ground and the secondary winding in a slightly different manner. The remaining circuits remain substantially the same except that line conductor 102 is grounded at the exchange. Relays 120, 140 and 195 are not used in this circuit and have been shown merely to show the ease by which this repeater may be used for both loop and grounded party lines.

When a subscriber on the line removes his receiver, relays 150, 170, 180 and 190 operate in a manner similar to that described for Fig. 1. The circuit for relay 150 may be traced as follows: from ground at the calling substation, conductor 101, back contact and armature 111, armature 123 and back contact, windings 124 and 125 of repeat coil RP; junction points 115 and 129 where the circuit divides, one path extending thru the winding of relay 150 to battery. A branch of this circuit extends from junction point 129, armature 133, thru the primary winding P of the polar impulsing relay 170, and thru the condenser C' to battery to charge the condenser C'. The charging current flowing thru the primary winding P is sufficient and is in a direction to operate relay 170 to its operated position to close its contacts 171 thereby operating pulse repeating relay 180. Slow releasing relay 190 is operated by relay 150 closing contacts 151 and by closure of contacts 181 by relay 180.

At contacts 191 relay 190 completes a circuit thru the secondary winding S to aid in the operation of relay 170 and for maintaining such relay in operated position after current flow in the primary winding P ceases, due to the cessation of the flow of charging current to condenser C'. The circuit thru the secondary winding S may be traced as follows: from ground at the calling substation over the line conductor 101 and the previously traced to junction point 115 and from thence by way of contacts 132, secondary winding S of relay 170, contacts 191, and thru resistance R1' to battery. At contacts 192 relay 190 connects ground thru resistance R2' to the secondary winding S but since the value of the resistance of R2' is greater than the resistance of the line when closed this connection does not change the direction of current flow thru the secondary winding. At contact 182 relay 180 connects ground to winding P thru the high resistance R3' and this circuit is effective after the condenser C' is charged to complete a preenergizing circuit thru the primary winding P in the reverse direction. This preenergizing circuit may be traced from ground contacts 192 and 182, high resistance R3', primary winding P of polar relay

170, contacts 133, junction point 129, and thru the winding of relay 150 to battery. The flow of current in this preenergizing circuit is in a direction to cause the release of relay 170 but due to the high resistance of resistance R3' this flow of current is small and is ineffective at this time to release relay 170 due to the flow of current through the second winding S previously described which predominates thereover. The polar pulsing relay 170 therefore remains in operated position until the line is opened. Fig. 4 now illustrates diagrammatically all the circuits in the impulsing network which are now completed.

At contacts 183 and 193 relays 180 and 190 close a bridge, including resistance R' and windings 126 and 127, across conductors 103 and 104 to cause the operation of the relays in the line circuit in the same manner as described for Fig. 1. Since the operation of the automatic switching apparatus is well-known and is the same as that described in connection with Fig. 1, no further explanation of such operations will be described.

The calling subscriber will now dial the number of the desired called subscriber. When the calling device CD is operated to open the line circuit, the local circuit for discharging condenser C' is effective to cause the release of polar pulsing relay 170. This local circuit may be traced from battery, condenser C', primary winding P of relay 170, contacts 133, junction point 129 and thru the winding of relay 150 back to battery. The flow of current thru the primary winding P in this local discharge circuit is sufficient and is in the proper direction to cause the polar pulsing relay to be operated to its released position thereby opening contacts 171 to release pulse repeating relay 180. Also when the line is opened the current flow thru the secondary winding S is reversed to assist in releasing relay 170 and to maintain such relay in released position as long as the line is open. Since the line is open the current flow thru the secondary may be traced over the following path: from ground at contacts 192, resistance R2' to junction point 184 where the current divides, one path extending thru resistance R1' to battery and the other path extending from the junction point 184, thru the secondary winding S, contacts 132, junction points 115 and 129, and thru the winding of relay 150 to battery. The current flow in this latter path thru the secondary winding S is sufficient and is the proper direction to assist the primary winding P to release relay 170 and for maintaining relay 170 in released position after the discharge current disappears. At contacts 182 relay 180 disconnects ground thru high resistance R3' to open the local preenergizing circuit thru the primary winding P. Secondary winding S maintains the polar relay 170 in its released position until the line is again closed.

When the calling device CD closes the line after the first pulse, the previously traced circuits for relay 150 and the charging circuit for condenser C' thru the primary winding P of relay 170 are again closed. Also, since the resistance value of R2' is greater than the resistance value of the line when closed current now flows thru the secondary winding S in a direction to aid the charging current thru the primary winding P of relay 170 to cause relay 170 to quickly operate to its operated position. This circuit may be traced from ground at the substation over line conductor 101 to junction point 115, contacts 132, 75

secondary winding S, and resistance R1' to battery. The flow of current in this circuit also maintains relay 170 in operated position after condenser C' is charged and after the preenergizing local circuit, including resistance R3, is closed in the same manner as previously described.

Further dial impulses cause similar operations of relays 170 and 180 and the latter relay at contacts 183 repeats the impulses to the automatic switch train to complete the desired connection in the well-known manner.

After conversation and in response to replacing the receiver relays 150, 170 and 180 release and after an interval slow release relay 190 likewise releases to open the local circuit thru the secondary winding S. The apparatus is now at normal and may be used on subsequent calls.

Incoming calls to this line are similar to that described for Fig. 1 except that ringing current is applied only to line conductor 103 to operate ringing control relay 160. Relay 160 at 161 operates ringing relay 110 to repeat the ringing code out over conductor 101. The called party, upon recognizing his code ring, removes the receiver thereby completing the circuits for relays 150, 170, 180 and 190 during a silent ringing period at which time relay 130 is in deenergized position. At contacts 183 and 193 relays 180 and 190 close a bridge across conductors 103 and 104 to cut off the ringing current being transmitted from the connector switch.

While the invention has been described in connection with a long telephone party line heavily loaded with ringers, it will be obvious that this impulsing arrangement is also adaptable for use in systems other than telephone systems where there is need for impulsing over long lines having similar characteristics.

What is claimed is:

1. In a signalling system, a line, an impulsing relay having a first and a second winding, a circuit including said first winding and said line in series completed in response to the closure of said line for momentarily energizing said first winding by current flow in one direction to operate said relay to its operated position, a circuit including said second winding and said line in series completed in response to the closure of said line for energizing said second winding by current flow in said one direction to assist in the operation of said relay and for maintaining said relay in operated position, a local circuit for said first winding ineffective when the line is closed and effective in response to opening said line for momentarily reversing the direction of flow of current thru said first winding to operate said relay to its released position, and another local circuit including a resistance in series with said second winding ineffective when the line is closed and effective in response to opening said line for reversing the direction of current flow thru said second winding to assist in operation of said relay to its released position and for maintaining said relay in its released position.

2. In a signalling system, a line, an impulsing relay having a primary winding and a secondary winding, a circuit including said primary winding and said line in series completed in response to the closure of said line for energizing said winding to operate said relay, a circuit including said secondary winding and said line in series completed in response to the closure of said line for energizing said winding to assist in the operation of said relay and for maintaining said relay

in operated position, and means for reversing the flow of current thru both said primary and secondary windings in response to the opening of said line for energizing said windings in the reverse direction to release said relay.

3. In a signalling system, a line, an impulsing relay having a primary winding and a secondary winding, a circuit including said primary winding and said line in series completed in response to the closure of said line for energizing said winding to operate said relay, a circuit including said secondary winding and said line in series completed in response to the closure of said line for energizing said winding to assist in the operation of said relay and for maintaining said relay in operated position, and local circuits for both said primary and secondary windings ineffective during the time said line is closed and effective in response to the opening of said line to reverse current flow thru both said primary and secondary windings in their respective local circuits for energizing said windings in the reverse directions to release said relay.

4. In a signalling system, a line, an impulsing relay having a first and a second winding, a condenser, a first line relay, a second line relay, means for closing said line, a circuit for operating said first and second line relays in series with said line completed in response to the closure of said line; a circuit including said first line relay, said line, said first winding of said impulsing relay, and said condenser in series for charging said condenser and for operating said impulsing relay to its operated position completed in response to the closure of said line, a slow relay operated in response to the operation of said line relays; a circuit including the second winding of said impulsing relay, said line and said second line relay in series for assisting in the operation of said impulsing relay completed in response to the operation of said slow relay, a resistance having a resistance value greater than the resistance value of the line when closed and having a resistance value less than the resistance value of the line when open; a local circuit including said first line relay, said second winding of said impulsing relay, and said resistance in series completed in response to the operation of said slow relay, said local circuit being ineffective when the line is closed, a local discharge circuit for said condenser including said first winding of said impulsing relay and said second line relay in series, said local discharge circuit being ineffective when the line is closed, means for transmitting impulses over said line by opening and closing said line whereby said first local circuit and said local discharge circuit are both rendered effective in response to each opening said line for reversing the direction of current flow in said first and second windings of said impulsing relay to cause the operation of said relay to its released position, and a pulse repeating relay controlled by said impulsing relay for repeating said impulses over an outgoing line.

5. In a signalling system, a line, an impulsing relay having a first and a second winding, a line circuit for said first winding including said line and said first winding in series, a local circuit for said first winding excluding said line, a line circuit for said second winding including said line and said second winding in series, a local circuit for said second winding excluding said line, means for transmitting impulses over said line by alternately opening and closing said line, and means comprising said line circuit in

series with said first winding and said line circuit in series with said second winding for operating said relay to its operated position in response to each line closure by current flow over said line circuits in the same direction thru said first and second windings and comprising said local circuit for said first winding and said local circuit for said second winding for operating said relay to its released position in response to each line opening by current flow over said local circuits thru both said windings in a direction opposite to that of the current flow in said line circuits.

6. In a signalling system, a line, an impulsing relay having a first and a second winding, a line circuit for said first winding including said line and said first winding in series, a local circuit for said first winding excluding said line, a line circuit for said second winding including said line and said second winding in series, a local circuit for said second winding excluding said line, means for transmitting impulses over said line by alternately opening and closing said line, and means comprising both said line circuit and said local circuit for said first winding and comprising both said line circuit and said local circuit for said second winding for reversing current flow thru said first and second windings in response to each opening and closing of said line to alternately release and operate said relay in accordance with the operation of said transmitting means.

7. In combination, a line, a relay having a first and a second winding, a condenser in series with said first winding; a charging circuit for said condenser including said line, said first winding and said condenser in series for operating said relay to attract its armature to its attracted position in response to closing said line, a discharging circuit for said condenser including said first winding and said condenser in series and excluding said line for operating said relay to release its armature to its released position in response to opening said line, a circuit for said second winding including said line and said second winding in series for assisting said charging circuit to operate said relay to its attracted position in response to closing said line and for maintaining said relay in its attracted position after said condenser is charged, and another circuit for said second winding excluding said line for assisting said discharging circuit to operate said relay to its released position in response to opening said line and for maintaining said relay in its released position after said condenser is discharged.

8. In combination, a line circuit, an impulsing relay having a first and a second winding, a condenser; an impulsing circuit including said line circuit, said first winding and said condenser in series; another impulsing circuit including said line circuit and said second winding in series for assisting said first impulsing circuit, a local circuit for said second winding excluding said line circuit, another local circuit for said first winding including said first winding and said condenser in series and excluding said line circuit, and a sender at the remote end of said line circuit for closing and opening said line circuit to control the operation of said relay over said impulsing circuits in response to closing said line circuit and to control the release of said relay over said local circuits in response to opening said line circuit.

9. In combination, a line circuit, an impulse

relay having a first and second winding, a condenser, a charging circuit for said condenser including said first winding and said line circuit in series, a local discharging circuit for said condenser including said first winding and said condenser in series and excluding said line circuit, a circuit for said second winding including said second winding and said line circuit in series, a resistance, and a local circuit for said second winding including said second winding and said resistance in series and excluding said line circuit.

10. In a signalling system, a line, an impulsing relay having a primary winding and a secondary winding, a condenser; a circuit for charging said condenser including said line, said primary winding and said condenser in series completed in response to the closure of said line for operating said relay, a circuit including said secondary winding and said line in series completed in response to the closure of said line for assisting in the operation of said relay and for maintaining said relay in operated position after said condenser is charged and while said line is closed, a resistance having a resistance value greater than the resistance value of said line when closed, said resistance connected in a local circuit in series with said secondary winding and connected in shunt of said line, and means for discharging said condenser thru said primary winding and for establishing current flow over said local circuit including said secondary winding and resistance in series in response to opening said line to thereby reverse current flow thru both said primary and secondary windings to release said relay.

11. In a signalling circuit, a line, an impulsing relay having a primary and a secondary winding, a condenser; a circuit for charging said condenser including said line, said primary winding and said condenser in series completed in response to the closure of said line; the condenser charging current in said circuit thru said primary winding being sufficient and in a direction to operate said relay, a circuit including said secondary winding and said line in series completed in response to the closure of said line for assisting in the operation of said relay and for maintaining said relay in operated position after said condenser is charged, a local circuit for reversing the current flow in said secondary winding, a local circuit for discharging said condenser thru said primary winding, both said local circuits effective in response to opening said line to reverse the current flow thru said primary and secondary windings to release said relay, and said local secondary circuit maintaining said relay in its released position after the discharging current in said local primary circuit is dissipated.

12. In a signalling system, a line, an impulsing relay having a primary and a secondary winding, a first circuit including said line and said secondary winding in series, a condenser; a second circuit including said line, said primary winding and said condenser in series; means for closing said line to establish current flow over said first circuit thru said secondary winding and to charge said condenser thru said primary winding by current flow over said second circuit to operate said relay, a local discharge circuit for said condenser including said primary winding, means for causing said condenser to discharge thru the primary winding over said local circuit in response to opening said line thereby reversing

the current thru said primary winding to release said relay, and another local circuit effective in response to opening said line for reversing the current flow thru said secondary winding to assist in releasing said relay to its released position.

13. In a signalling system, a line, an impulsing relay having a primary and a secondary winding, a first circuit including said secondary winding and said line in series, a condenser; a second circuit including said line, said primary winding and said condenser in series; means for closing said line to establish current flow over said first circuit thru said secondary winding and to charge said condenser thru said primary winding by current flow in said second circuit to operate said relay, the current flow in said first circuit maintaining said relay operated after the condenser in said second circuit is fully charged, a local discharge circuit for said condenser including said primary winding, a local circuit for said secondary winding, means responsive to opening said line for rendering both said local circuits effective to reverse the current flow thru said primary and secondary windings to release said relay, and said local secondary circuit being effective after the discharge current is dissipated in said local primary circuit to maintain said relay in its released position.

14. In a signalling system, a line, an impulsing relay having a primary and a secondary winding, a first circuit including said secondary winding and said line in series, a condenser; a second circuit including said line, said primary winding and said condenser in series; means for closing said line to establish current flow over said first circuit thru said secondary winding and to charge said condenser thru said primary winding by current flow in said second circuit to operate said relay, means responsive to the operation of said relay for closing a preenergizing circuit for said primary winding, said preenergizing circuit effective after said condenser is charged to reverse the direction of current flow in said primary winding preparatory to releasing said relay, the current flow in said first circuit maintaining said relay operated after said condenser in said second circuit is fully charged, a local circuit for discharging said condenser thru said primary winding with current flow in the same direction as in said preenergizing circuit effective in response to opening said line to release said relay, a local circuit for reversing the current flow in said secondary winding effective in response to opening said line to assist in releasing said relay and for maintaining said relay released after the discharge current in said first mentioned local circuit is dissipated, and said last mentioned means opening said preenergizing circuit in response to the release of said relay.

15. In a signalling circuit, a line, an impulsing relay having a primary winding and a secondary winding, a condenser; a circuit for charging said condenser including said line, said primary winding and said condenser in series completed in response to the closure of said line; the condenser charging current thru said primary winding being sufficient and in a direction to operate said relay, a circuit including said secondary winding and said line in series completed in response to the closure of said line for assisting in the operation of said relay, a local circuit for reversing the current flow in said secondary winding, a local circuit for discharging said condenser thru said primary winding, and both said local circuits effective in response to the

opening of said line to reverse the current flow thru said primary and secondary windings to release said relay.

16. In a signalling system, a line, an impulsive relay having a primary and a secondary winding, a condenser, a local discharge circuit for said condenser including said primary winding, means for closing said line and for completing a charging circuit for said condenser over a circuit including said line and said primary winding in series, means responsive to the closure of said line for completing a circuit for said secondary winding in series with said line and for completing a local circuit for said secondary winding, said local discharge circuit and said local secondary winding circuit being ineffective when the line is closed, the condenser charging current in said charging circuit thru said primary winding be-

ing sufficient and in a direction to operate said relay, the current flow over the circuit including said line and said secondary winding in series being in a direction to aid in the operation of said relay and being sufficient to maintain said relay in operated position after said condenser is charged, said local discharge circuit and said local circuit for said secondary winding effective in response to opening said line to reverse the current flow in said primary and secondary windings to release said relay, the discharge current being sufficient and in a direction to release said relay and the current flow in the local circuit for the secondary being in a direction to aid in the release of said relay and sufficient to maintain said relay in its released position.
